UNITED STATES PATENT OFFICE.

THOMAS T. CUNNINGHAM, OF OSCEOLA, MISSOURI.

TONGUE-SUPPORT.

SPECIFICATION forming part of Letters Patent No. 364,337, dated June 7, 1887.

Application filed March 4, 1887. Serial No. 239,727. (No model.)

To all whom it may concern:

Be it known that I, THOMAS T. CUNNINGHAM, a citizen of the United States, residing at Osceola, in the county of St. Clair and State 5 of Missouri, have invented certain new and useful Improvements in Wagon and Carriage Tongue Supporters; and I do hereby declare the following to be a full, clear, and exact description of the invention, such as will enable 10 others skilled in the art to which it appertains to make and use the same.

My invention relates to supporters for the tongues of vehicles; and it consists in certain details of construction, to be hereinafter specifically described, and pointed out in the 15 claims.

The object of my said invention is to provide a regulated support for vehicle-tongues, to elevate the same when the vehicle is not in 20 use, and to take the strain off the draft animals and support the tongue when in use.

In the accompanying drawings, which fully illustrate my invention, Figure 1 is a plan view of my device as applied to a vehicle. Fig. 25 2 is a sectional view, and Fig. 3 represents details of the same.

A is a strong spiral spring, and B a metallic loop passing through said spring from front to rear, having its front ends terminating in 30 hooks b, which abut against the first coil of the spring, and having at its looped or rear end a chain, C, which is usually permanently attached to the eye or loop d of a plate, D, secured to the top of the forward bolster, E, 35 and through which plate the bolster pin F passes.

B' is a metallic loop, similar to the loop B, above described, but passed through the 40 spring A in the opposite direction, its hooks b' pressing or abutting against the rear or last coil of the spring, and having at its front or looped end a chain, G, provided with a hook, g, which is to connect with a metallic plate, H, on the evener, provided with an eye or 45 loop, h, through which latter the end of the chain G is passed, and the tongue of the vehicle being elevated to the desired position the hook g is fastened in one of the links of the chain G. Thus as the loops B and B' are 50 drawn from opposite directions their hooks will compress the spring A, when the weight of the vehicle-tongue draws on the chains C and G, and the expansion of the spring will keep the tongue elevated and take the strain

off the draft-animals and prevent or deaden 55 shocks when obstacles are encountered by the wheels.

The end of the chain C is usually permanently attached to the eye of the bolster-plate D, or it may be removably attached by a split 60 ring or snap-hook, if desired, while the chain G is connected with the evener-plate by means of the snap g passing through the eye h at such length as will properly elevate the tongue, so that the spring will equalize and deaden all 65 shocks and jars.

Having thus fully described my invention, what I claim therein as new, and desire to secure by Letters Patent, is—

1. A vehicle-tongue supporter consisting of 70 a spiral spring inclosing two oppositely-extending metallic loops, having their free ends bent into hooks which retain the end coils of the spring, and their looped or linked ends attached to chains, one permanently connected 75 with a plate on the top of the front bolster of the vehicle, the other adjustably connected with a like plate on the evener, which evener is secured to the pole to elevate the tongue to any desired pitch, all substantially as described.

2. In a vehicle-tongue supporter, the combination of the inclosing spiral spring A, the loops B and B', passing through the spring and having the hooked ends b and b', the 85 chains C and G, the former connecting with the bolster-plate and the latter having the hook g arranged to pass through a loop or eye on the evener-plate and connect with one of the links of said chain, all substantially as described.

3. The encircling spring A, in combination with the loops B and B', passing through said spring and retaining it by their hooked ends abutting against the end coils of the spring, 95 the chains C and G, the latter arranged to regulate the elevation of the tongue by the adjustment of the hook g through the loop on the evener-plate and one of the chain-links, the said evener-plate H, and the bolster-plate 100 D, having the eye or loop d, all substantially as described.

In testimony whereof I affix my signature in presence of two witnesses.

THOMAS T. CUNNINGHAM.
